UNITED STATES PATENT OFFICE

SAMUEL I. GOLDBERG, OF NEW YORK, N. Y.

DESIGN FOR A LIGHTING FIXTURE

Application filed March 8, 1930. Serial No. 34,785. Term of patent 7 years.

To all whom it may concern:

Be it known that I, SAMUEL I. GOLDBERG, a citizen of the United States, residing at 666 West End Avenue, in the city of New York, in the county of New York, and State of New York, have invented a new, original, and ornamental Design for a Lighting Fixture, of which the following is a specification, reference being had to the accompanying drawing, forming part thereof.

Figure 1 is a perspective view of a front and bottom view of a lighting fixture of my new design.

Figure 2 is a plan view of the top of a lighting fixture showing my new design.

I claim:

The ornamental design for a lighting fixture, as shown.

SAMUEL I. GOLDBERG.
